United States Patent Office

Des. 215,239

Patented Sept. 16, 1969

215,239

FORK OR SIMILAR ARTICLE

James Russell Price, Esmond, R.I., assignor to
Textron Inc., Providence, R.I.

Filed Dec. 24, 1968, Ser. No. 15,118

Term of patent 14 years

Int. Cl. D7—03

U.S. Cl. D54—12

FIG. 1

FIG. 2

FIG. 3

FIG. 4

FIG. 5

FIG. 1 is a front elevation of a fork or similar article showing my new design;

FIG. 2 is a side elevation thereof;

FIG. 3 is a rear elevation thereof;

FIG. 4 is an end view thereof; and

FIG. 5 is a cross-section along line 5—5 of FIG. 1 on enlarged scale.

The essential features of the design reside in the full line portions of the drawing, the conventional tines being shown in broken lines.

I claim:

The ornamental design for a fork or similar article, substantially as shown and described.
